UNITED STATES PATENT OFFICE.

HERMAN HESSE, OF EASTON, PENNSYLVANIA.

LETTER-OPENER.

1,152,628.

Specification of Letters Patent. Patented Sept. 7, 1915.

Application filed March 31, 1915. Serial No. 18,211.

To all whom it may concern:

Be it known that I, HERMAN HESSE, a subject of the Emperor of Germany, residing at Easton, in the county of Northampton and State of Pennsylvania, have invented certain new and useful Improvements in Letter-Openers, of which the following is a specification.

The present invention relates to envelop openers and has for its object to provide a device that is adapted to be loosely placed between the folds of a letter or papers contained in an envelop or wrapper, so that when the same arrives at its destination it can be quickly and neatly torn open, thus facilitating the opening of the mail.

Letter openers of similar characters have been known but the same as far as I am aware have been attached to the envelop. This is objectionable because the process of attaching the device to the envelop causes loss of time, which becomes considerable with much mail. Furthermore, the particular fastening means of the device adds to the weight of the letter or parcel and renders the cost of manufacture of the opener somewhat expensive.

To obviate these drawbacks is the object of my invention.

My invention will be clearly understood by reference to the accompanying drawing, in which similar reference characters denote corresponding parts and in which—

Figure 1 is a perspective view of a sealed envelop on which my new device is shown in dotted lines; Fig. 2 is an enlarged vertical section on line 2—2 of Fig. 1; Figs. 3, 4 and 5 illustrate different modifications of my device.

The device consists of a flat member *a* of any suitable light and more or less rigid material, preferably paste board or the like. This member may be made in any suitable shape, such as in form of a square (Fig. 1), ring (Fig. 3), circular disk (Fig. 4) or triangle (Fig. 5). Suitably attached to said member is a cord *b* (Figs. 1-3), ribbon (Fig. 4), or wire (Fig. 5), made slightly longer than the length of that edge of the envelop or wrapper along which it is to extend.

The flat member *a* is adapted to be placed loosely between the folds of a letter *c* or papers and near one of the side edges of the folded parts. The flexible member *b*, as cord, ribbon or wire is folded over the back of the fold to extend along the same and to project outwardly from the opposite side of the envelop *d* or wrapper containing the letter or papers. When the envelop or wrapper, having been sealed, is received at its destination, the same can be quickly and neatly torn open by pulling on the protruding end of the ribbon, cord or wire, as indicated in Fig. 1.

The flat rigid piece *a* of my device may be utilized for advertising purposes or for various kinds of announcements or the like, as indicated in Figs. 3 and 4.

If made of a solid piece as in Figs. 1, 4 and 5, the same may have a perforation through which the cord, ribbon or wire may be passed to be tied to the piece *a*.

In operation the flat rigid part is held from sliding by leaning against the fold of the letter or parcel.

The rigid piece may, of course, be made of such dimensions as to correspond with the size of the envelop. In that case it may be used without any letters, etc., and may itself serve as a medium for correspondence, in form of advertising cards, business cards, or the like.

Because of its simple, inexpensive construction and its adaptability as a medium for advertising announcements or similar purposes, my device becomes a very useful article.

What I claim and desire to secure by Letters Patent is:

1. An envelop opener, consisting of a rigid part of light material and a flexible member connected at one end thereto, said rigid part serving as anchorage for said flexible member and being adapted to be placed loosely into the envelop and the flexible member to be folded so as to extend from said anchorage toward the opposite end of and along the edge of the envelop which is to be torn open and to protrude with its free end outwardly from the sealed envelop.
2. The combination with a folded letter

or the like and an envelop or wrapper containing the same, of a flat rigid piece and a flexible member connected to said piece, said piece being adapted to be loosely placed between the folded contents of the envelop or wrapper, and said flexible member to be folded so as to extend toward the opposite end of said piece and over the back of the

fold and to protrude with its free end from within the envelop or wrapper.

In testimony whereof I affix my signature in presence of two witnesses.

HERMAN HESSE.
